[57] **CLAIM**

The ornamental design for a set of stacked trays, as shown and described.

DESCRIPTION

FIG. 1 is a top rear left side exploded perspective view of a set of stacked trays, showing my new design;

FIG. 2 is a top front left side perspective view thereof, with the top tray shown in an alternate position;

FIG. 3 is a front elevational view thereof with the top tray in a closed position;

FIG. 4 is a right side elevational view thereof;

FIG. 5 is a rear elevational view thereof; and

FIG. 6 is a bottom plan view thereof.
